REFRIGERATED STORAGE CABINET

Harry Fowler, Trenton, N. J.

Application March 1, 1946; Serial No. 651,107

5 Claims. (Cl. 62—89)

1

2

My invention relates to refrigerated constructions and particularly to refrigerators having relatively movable storage chambers. The storage compartments within refrigerators heretofore constructed for use in homes, hotels, stores and elsewhere have not been readily accessible, especially when they are made relatively deep since it then is difficult or impossible to reach articles in the rear of the storage compartment. Furthermore, prior refrigerated structures have had limited utility because they have been designed to maintain all portions of all compartments at the same temperature. They therefore cannot be used for the storage of articles at different temperatures or for the quick freezing of products and are not variable in operation so as to possess the desired versatility. Such constructions also have only limited storage capacity in comparison with the wall space which they occupy.

In accordance with my invention these objections and limitations of prior refrigerated structures are overcome and constructions are provided which have increased accessibility and utility and have greater storage capacity in relation to the wall space occupied thereby. A further and most important feature of my invention resides in the provision of separate storage compartments which may be maintained at different temperatures for the storage of products such as milk and fruit at, say, 40° F., and for the storage of frozen foods or for the freezing of articles at temperatures of, say, +10° F. to -10° F.

These advantages are preferably attained by equipping the refrigerator with relatively movable chambers arranged to afford access thereto from at least two sides so that they may be made of any desired depth and yet be readily accessible throughout their interior. One chamber may be stationary and contain refrigerating means for maintaining the stationary chamber at a desired low temperature. The relatively movable chamber may be maintained at a higher or desired temperature by the separately thermostatically controlled evaporator for it may be cooled by the action of the refrigerating means in the stationary chamber. In this way the accessibility and utility of refrigerators may be increased and a single construction may provide both freezing and storage chambers of the desired capacity without occupying excessive wall space.

The principal object of my invention is to provide a novel type of refrigerator embodying relatively movable storage chambers.

Another object of my invention is to render the section in its movement into opened and closed

storage space of refrigerated structures more readily available.

A further object of my invention is to provide a novel refrigerator having storage compartments which may be maintained at different temperatures.

These and other objects and features of my invention will appear from the following description thereof in which reference is made to the figures 10 of the accompanying drawings.

In the drawings:

Fig. 1 is a perspective of a typical form of refrigerator embodying my invention;

Fig. 2 is a horizontal sectional view of the construction illustrated in Fig. 1;

Fig. 3 is a vertical sectional view of a portion of the construction illustrated in Fig. 1 illustrating a detail thereof;

Fig. 4 is a horizontal sectional view of an alternative of a refrigerator embodying my invention;

Fig. 5 is a front elevation of the device shown in Fig. 4; and

Fig. 6 is a perspective of a further alternative of a construction embodying my invention.

In that form of my invention shown in Figs. 1 and 2, the refrigerator embodies a base 2, a stationary storage section 4 and a movable storage section 6. The structure is provided with an insulated rear wall 8 which preferably is formed integral with the base 2 and stationary section 4 and cooperates with the movable section 6, to close the rear thereof when the movable section is in its normal closed position.

The movable section 6 is pivotally mounted adjacent the vertical free edge 10 of the rear wall 8 by means of hinges 12 and is formed to fit closely adjacent the upper surface 14 of the base 2 and the lateral face 16 of the stationary section 4 when in its normal closed position. A sealing gasket 18 extends along the horizontal front edge of the base 2 and along the vertical front edge of the stationary section 4 and along the horizontal top edge of the latter section to engage and cooperate with the movable section 6 so that it affords a tight joint about the edges of the movable section when closed but permits ready movement of the section 6 to its opened position as shown in Fig. 1.

The bottom 20 of the movable section 6 is provided with a downwardly facing track 22 which cooperates with rollers 24 or other suitable means located on the upper surface 14 of the base 2 to support the free edge of the movable section so as to prevent sagging thereof and to guide the section in its movement into opened and closed

positions. The track 22 also may have stop means 23 thereon as shown in Fig. 3 and arranged to be engageable with stop means 25 on the base 2 to limit outward pivotal movement of the movable section 6 so that it will not strike the wall at the rear of the refrigerator and will not swing far enough to leave the outer edge unsupported.

The outer wall 27 of the movable section 6, shown at the left hand side in Figs. 1 and 2, is formed with a rearwardly extending portion 29 which overlaps and cooperates with the vertical end 10 of the rear wall 8 to form an insulated corner construction when the movable section is in its closed position. The hinges 12 are thus concealed and the end wall 27 may be suitably insulated to prevent the penetration of heat into the storage compartment of the movable section. The rearward projection of the rear corner of the portion 29 will not interfere with the opening of the movable section since such refrigerated structures are normally spaced a few inches from the wall for ventilation purposes. Therefore complete insulation of the section 6 may be assured.

As shown, the base 2 is provided on one side with drawers 26 or other storage means which may or may not be refrigerated, whereas the opposite side 28 of the base serves as a housing for a compressor and motor or other elements of the refrigerating mechanism (not shown). The stationary section 4 has a storage compartment 30 which is insulated about its top, bottom and side walls whereas the lateral face 16 of the compartment 30 may be suitably constructed and insulated to maintain the desired low temperature in the stationary section. This section preferably is designed to be maintained at a relatively low temperature, say from +10° F. to -10° F. for receiving frozen fruits, vegetables or other products or to serve as a quick freezing unit in which articles to be frozen may be placed. However, if desired the face 16 of the stationary section can be formed of metal or other heat conducting material for the purpose of refrigerating the movable section 6 when in its normal closed position.

Doors or drawers 34 are mounted on the stationary section to close the compartment 30 and are arranged to open in a direction toward the movable section 6 to provide access to the compartment 30 when the movable section 6 is swung to the open position shown in Fig. 1. The door or drawer fronts 34 preferably are formed of insulating material but may be formed of metal or other material which will transmit heat so that they combine to provide the equivalent of a refrigerated plate for reducing the temperature of the storage compartment 36 in the movable section 6. On the other hand the storage compartment 30 remains closed even when the movable section 6 is swung open so that there is no excessive heat loss or increase in temperature of the compartment 30 during normal use of the refrigerator.

As shown in Fig. 2 the stationary section 4 also is provided with a door 38 pivotally mounted on its opposite vertical wall 40 to provide access to the storage compartment 30 without moving the section 6 or to enable articles within the compartment 30 to be reached more easily. The stationary section 6 therefore may be of a width and depth considerably greater than has been possible heretofore so that its capacity may be relatively large without decreasing its accessibility or causing inconvenience to the user.

The movable storage compartment 6 is pro-

vided with an insulated top 42 and the bottom 20 thereof preferably also is insulated when the base 2 is not refrigerated and is designed for the storage of articles which do not require refrigeration. However, the bottom 20 may be uninsulated if the upper surface 14 of the base 2 is suitably insulated or if it is desired to refrigerate the base by withdrawal of heat through the movable section 6.

The front wall 44 and the end wall 27 of the section 6 are insulated but one of these walls, and preferably end wall 27, is provided with a door 48 which provides access to the storage compartment 36 of the movable section without moving the section with respect to the base and stationary section. The rear face 50 of the section 6 is uninsulated and preferably is entirely open but since it lies adjacent the rear wall 8 when the section is in its normal closed position there is little or no heat loss through the rear face. Similarly, the lateral face 52 of the movable section is uninsulated and is provided with a door 46 open throughout the greater part of its area to afford easy accessibility to products stored thereon. The face 52 also is uninsulated in those constructions in which the movable section is refrigerated by transfer of heat through the lateral face 16 of the stationary section 4.

The compartment 36 may thus be made relatively large and much wider and deeper than the sections of ordinary refrigerators of the prior art without inconvenience to the user or limiting access to its interior. Furthermore, in the preferred form of my invention the movable section 6 is refrigerated by a coil 54 mounted on the vertical rear wall 8 of the structure and in position to project into the storage compartment 36. This coil may be supplied with refrigerant under control of a thermostat connected in any conventional manner to the refrigerating system and suitably located as shown diagrammatically at 55 so as to maintain the compartment 36 at a predetermined temperature, say 40° F., independently of the temperature maintained in the stationary compartments.

The coils and refrigerating means employed for refrigerating the stationary section 4 may be of any preferred form or type, but I prefer to arrange the coils at 56 within the storage compartment 30 of the stationary section 4 in such a way that they serve as shelves or supports for the drawers 34 and thus assure the most adequate heat transfer for cooling or freezing the articles in the stationary section. The temperature of the compartment 30 in the stationary section may be maintained by an independent thermostat 55.

With this construction the wall space occupied by the refrigerator may be limited since the construction may be greater in depth than a conventional refrigerator and yet the interior of each compartment is fully accessible by reason of the doors or openings located on two or more sides of the compartment. Furthermore, the compartments may be maintained at different temperatures so that milk, fruit and similar products can be preserved in the movable storage compartment while frozen foods are stored in the stationary compartment.

In that form of my invention illustrated in Figs. 4 and 5, the refrigerator is provided with a central storage section 60 which cooperates with relatively movable sections 62 and 64 located on the opposite sides of the central section and above the opposite ends 66 of the base 68. Each of the sections 62 and 64 is hingedly supported at 70

adjacent one or the other of the outer vertical edge of an extended insulated rear wall 72. The sections 62 and 64 therefore may be moved into and out of the closed positions as shown in full lines in Fig. 5 wherein they cooperate with the central section and are refrigerated thereby. At the same time, the opposite outer faces of the compartments 62 and 64 are provided with doors 14 and 16 through which access to the compartments may be attained without moving the sections relative to the stationary central section 60. It will also be apparent as shown in Figs. 4 and 5 that the doors 14 and 16 may themselves be in the form of separate compartments which contain articles to be preserved and these compartments may project beyond the base if desired to provide the maximum storage capacity with a limited floor space and to render articles readily available to the user.

The central section 60 also is provided with an access door 78 so that articles may be stored in the central section and access may be had thereto either through the door 78 or through drawers 80 and 82 located on the opposite vertical faces of the central section which cooperates with the movable sections 62 and 64. These vertical faces may be insulated to maintain each compartment at a predetermined temperature independently of any other compartment or the vertical faces may be formed of metal or other material which will conduct heat readily so that they each serve as a refrigerating element for maintaining the storage compartments of the movable sections 62 and 64 at the desired low temperature. In order that one of the movable sections may be maintained at a different temperature from the other the fronts of drawers 80 and 82 may be formed of material having different heat transmitting and refrigerating characteristics. The coils 84 and 86 or other refrigerating means employed for cooling the movable sections of the refrigerator are preferably located on the rear wall 72 in position to project into the storage compartments of the movable sections and are located at 88 in the stationary section in position to form supports for the drawers 80 and 82 which open toward opposite vertical faces of the central stationary section 60.

The general assembly and movement of the sections in this form of my invention is similar to that previously described but the accessibility and utility as well as the capacity of the refrigerator can be greatly increased without a corresponding increase in the wall space or the use of separate refrigerated structures. Furthermore, three selected refrigerating temperatures may be maintained within the refrigerator whereas each compartment is accessible from at least two sides although access may be had to any one section without reference to any other.

As further illustrated in Fig. 6 the shelves, racks or other supports 90 for articles stored in the movable sections may themselves be pivoted for movement relative to the insulated outer walls of the section. For this purpose the shelves are mounted on a frame 92 pivoted on hinges 94 on the rear wall 8 of the structure. The pivots about which hinges 94 move are in axial alignment with the pivots 12 about which the section itself is movable and therefore the shelves and section may be moved together or independently as desired for the purpose of greater accessibility and utility.

While I have illustrated and described two particular forms of refrigerator embodying my invention it will be evident that the various ele-

ments are capable of many other arrangements and changes in form, size and combination without departing from the spirit of my invention. In view thereof it should be understood that the embodiments of my invention shown in the drawings and herein described are intended to be illustrative only and are not intended to limit the scope of my invention.

I claim:

10. A refrigerator comprising an insulated base, an insulated rear wall extending upward from said base, a stationary storage section located above said base and in front of said rear wall and having openings for access thereto in both the front and one side wall thereof, a movable storage section located above said base and pivotally mounted adjacent one end of said rear wall for movement in a horizontal plane into and out of a closed position in which one vertical face of the movable section is located adjacent said rear wall and another vertical face thereof is located adjacent said side wall of the stationary section, said vertical faces of the movable section each being uninsulated and each having an opening therein for access to the interior of the movable section, and refrigerating means mounted on said rear wall in position to refrigerate said movable section when the latter is moved to said closed position.
20. A refrigerator having an insulated base, an insulated rear wall extending upward from said base, a stationary section located above said base and in front of said rear wall and having opposite side walls each of which has openings therein for access to the interior of the stationary section, said rear wall extending in opposite directions on each side of said stationary section, movable storage sections located above said base and on each side of said stationary section and pivotally mounted adjacent the opposite ends of said rear wall, said movable storage sections each being movable in a horizontal plane into and out of a closed position in which one vertical face of the movable section is located adjacent said rear wall and another vertical face is located adjacent a side wall of said stationary section, said faces of the movable sections being uninsulated and each having an opening therein for access to the interior of the movable sections, and means for refrigerating said stationary section whereby said movable sections will be refrigerated while in said closed positions.
30. A refrigerator comprising an insulated base, an insulated rear wall extending upward from said base, a stationary storage section located above said base and in front of said rear wall and having openings for access thereto in both the front and one side wall thereof, a movable storage section located above said base and pivotally mounted adjacent one end of said rear wall for movement in a horizontal plane into and out of a closed position in which one vertical face of the movable section is located adjacent said rear wall and another vertical face thereof is located adjacent said side wall of the stationary section, said vertical faces of the movable section each being uninsulated and each having an opening therein for access to the interior of the movable section, and refrigerating means mounted on said rear wall in position to refrigerate said movable section when the latter is moved to said closed position, said movable section having a door movable independently of said section for providing access to the interior thereof while the movable section remains in said closed position.
- 40.
- 50.
- 60.
- 70.
- 75.

4. A refrigerator comprising an insulated base, an insulated rear wall extending upward from said base, a stationary storage section located above said base and in front of said rear wall and having openings for access thereto in both the front and one side wall thereof, a movable storage section located above said base and pivotally mounted adjacent one end of said rear wall for movement in a horizontal plane into and out of a closed position in which one vertical face of the movable section is located adjacent said rear wall and another vertical face thereof is located adjacent said side wall of the stationary section, said vertical faces of the movable section each being uninsulated and each having an opening therein for access to the interior of the movable section, and refrigerating means mounted on said rear wall in position to refrigerate said movable section when the latter is moved to said closed position, said refrigerating means serving to maintain said stationary chamber at a temperature lower than that at which said movable storage section is maintained.

5. A refrigerator having an insulated base, an insulated rear wall extending upward from said base, a stationary section located above said base and in front of said rear wall and having opposite side walls each of which has openings therein for access to the interior of the stationary section, said rear wall extending in opposite directions on each side of said stationary section, movable storage sections located above said base and

5
